COIL STRIPPER

William H. Blount, West Brookfield, Mass., assignor to Sleeper & Hartley, Inc., Worcester, Mass., a corporation of Massachusetts

Application November 4, 1935, Serial No. 48,074

2 Claims. (Cl. 153—64)

This invention relates to an attachment for a coiling machine particularly, but for any machine in which a wire is formed into any particular shape, and the principal object is to provide a simple compact and effective means for stripping the coil or other article made by that machine off the arbor on which it is formed. Another object is to provide means whereby the stripping mechanism will be operated from a rotating part of the machine and the parts will be restored to normal active position automatically after the stripping has taken place. A further object is to provide mechanism located in a rotating tube for performing the operation of stripping and keeping the parts for returning the arbor from turning during the rotating operation.

Other objects and advantages of the invention will appear hereinafter.

20 Reference is to be had to the accompanying drawing, in which

Fig. 1 is an elevation partly in section of a preferred embodiment of the invention shown attached to a coiling machine;

25 Fig. 2 is a similar view of the lower part of the stripping mechanism showing the coil stripped from the arbor;

Fig. 3 is an elevation in the direction of the arrow 3 in Fig. 1 showing the cam for operating the stripper;

Fig. 4 is a sectional view on the line 4—4 of Fig. 1, and

Fig. 5 is a sectional view similar to part of Fig. 1 showing the parts in the stripping position.

This invention is shown as an attachment to

a coiling machine, very little of the coiling machine being shown, but the frame 19 is provided

with a bracket 10 on which is placed a second bracket 11 to which is pivoted a lever 12. One end of this lever has an operating rod 13 con-

10 end of the lever 11 has a projection 12 connected with a link 14 which has a projection 15 preferably. This link is pivoted on a bracket 16 on the frame 19. The link is adapted to be operated by a rotating cam 17 on a shaft 18 which 45 is rotated continuously when the machine is being operated.

The bracket 10 is mounted on the frame 19 of the machine and this bracket carries the usual lever 20 operated by suitable mechanism through 50 a link 21. The lever 20 carries a yoke 22 operating a spool 23 adjustably fixed on screw threads on a tube 24. Nuts 25 hold it in adjusted position and, as usual, the operation of the link raises and lowers this tube whenever necessary.

55 On the frame 19 is located a guide 26 for the

tube 24 and a bearing 27 for a gear 28 which is operated in the usual way by the machine and which meshes with a long pinion 29 integral with the tube 24. Thus the rotation of the gear 28 rotates the tube 24 irrespective of the position of the tube vertically. All the parts in the tube 24 rotate except the arbor.

The parts just described are old and constitute a part of the machine now on the market.

On the free end of the lever 12 is a yoke operating a spool 30. This spool has a downwardly extending skirt 31 with a longitudinal slot 32. Inside the skirt is a hollow cylinder 33 which has a radial pin 34 extending into the slot 32 to keep this cylinder 33 from turning relative to the spool 30.

An arbor 35 passes down through the spool and cylinder 33 clear to the bottom of the mechanism. On the arbor near the top is pinned a disc 36 in the bottom of the cylinder 33. Below this disc is a head 37 on a hollow spindle 38 which has a longitudinal passage or course to receive the arbor. The spindle 38 is screwed tight to the cylinder 33. Resting on the disc 36 and also engaging the top of a cylindrical passage in the cylinder 33 is a spring 39. This spring tends at all times to hold down the spindle 38 but yields, as shown in Fig. 5, to allow the stripping action to take place. This spindle is threaded and a nut 40 is mounted on it engaging the bottom of the cylinder 33, but the skirt 31 is free to move up and down with respect thereto.

The arbor 35 projects down through a bushing 41 on the cylinder 24. The spindle 38 projects down into this part of the mechanism and has screwed to the bottom a head 42 which is shown as having a pin 43 for coiling the wire. So it will be seen that the arbor projects down through the bottom of this head 42 when the machine is operating as shown in Fig. 1. Every time the cam 17 engages the projection 15, the rod 13 will be drawn down and the arbor 35 will be drawn up to the position shown in Fig. 2, thus dislodging the work 44. This is possible on account of the spring 39. After the cam 17 passes beyond the projection 15, the spring 39 will restore the arbor 35 to the position shown in Fig. 1.

This constitutes a simple and compact means for adjusting the work and restoring the coiling arbor to operative position. The parts are capable of the necessary adjustment and are all tight to prevent the admission of dust. 50

Having thus described my invention and the advantages thereof, I do not wish to be limited to the details herein disclosed, otherwise than

as set forth in the claims, but what I claim is:—
1. In a device of the character described, the combination with an arbor, of a hollow spindle through which the arbor extends, means for pulling 5 the arbor along the spindle, means for yieldingly moving the arbor in the opposite direction, a cylinder surrounding the yielding means, a skirt surrounding the cylinder to which said pulling means is connected and which is capable 10 of sliding relative to the cylinder, and means for preventing a relative rotary motion between the skirt and cylinder.

2. In a device for stripping the work from an arbor, the combination with the arbor, of a hollow rotary spindle surrounding the arbor, a cylinder surrounding the spindle, means connected with the end of the arbor for forming an article from wire or the like, means for moving the arbor longitudinally with respect to the spindle for dislodging said article, and a spring in the cylinder adapted to be compressed by said motion of the arbor and to restore the arbor to active condition. 10
